UNITED STATES PATENT OFFICE.

JOHN WESLEY KERLIN, OF NEW BRUNSWICK, NEW JERSEY.

TANK.

Application filed September 28, 1921. Serial No. 503,885.

To all whom it may concern:

Be it known that I, JOHN W. KERLIN, a citizen of the United States, and a resident of New Brunswick, in the county of Middlesex and State of New Jersey, have invented a new and Improved Tank, of which the following is a full, clear, and exact description.

This invention relates to tanks and has for an object to provide an improved construction wherein fire in the tank or an explosion in the tank is rendered impossible or at least substantially impossible.

Another object is to provide a tank in which combustible and explosive material may be provided and at the same time protected against fire either continuously or at intervals.

A still further object of the invention is to provide a tank in which the parts are so formed that one or more walls or sheets of water is provided around the tank for preventing explosion or burning of the contents of the tank.

25 In the accompanying drawings—

Figure 1 is an elevation of a tank showing one embodiment of the invention, certain parts being broken away and shown in section for illustrating certain detail structures.

Figure 2 is a top plan view of the structure shown in Figure 1, certain parts being broken away.

Figure 3 is a detail fragmentary sectional view through Figure 1 approximately on line 3—3.

Referring to the accompanying drawings by numeral, 1 indicates an inner tank of any desired kind which is provided with a vent pipe 2 having a bent over upper end 3 whereby any fumes or vapor from the tank may be readily prevented. The tank 1 may be used to store gasoline or any other substance desired and is preferably provided with a manhole 4 opposite the manhole 5 in the outer casing 6. A pipe 7 acts as a supply and also outlet pipe for the tank 1. This pipe, as shown particularly in Figure 3, is connected with a casting 8 bolted or otherwise rigidly secured to the tank 1, said casting having a bore registering with the pipe 7 and with an aperture 9 in tank 1. A covering ring or disk 10 is bolted or otherwise secured to casting 8 and to part of the casing 6 whereby access may be had to the space between the casing 6 and tank 1 at any time.

In addition to this means for permitting access, a number of plates 11 are bolted or otherwise rigidly secured to the casing 6 in such a manner as to be readily removed for access to the space between the tank 1 and casing 6.

A thermometer 12 is arranged interiorly of tank 1 and is connected with a suitable pipe 13 which extends to some signal mechanism whereby when the thermometer 12 shows a certain temperature, a signal will be sounded or if desired, water could be automatically turned onto the pipe 14 for supplying the space between tank 1 and casing

6 with water and for causing a suitable overflow of the casing. Preferably, however, a signal is connected with the thermometer of pipe 13 and water is manually turned on to the pipe 14 which is discharged into the space between tank 1 and casing 6 as shown in Figure 1. This forms a wall of water surrounding tank 1 and said wall passes upwardly and over the top of tank 1 until it finally is discharged out the central top opening 15. This opening is flared over, so that the discharge will be substantially even throughout and will fall on the top 16.

An annular semi-tubular baffle 17 is arranged on the top 16 a short distance from the opening 15. Other baffles 18 and 19 are also connected with the top 16 to more evenly distribute the water over the top and to cause it to fall in a comparatively even sheet over the outside of the casing 6 whereby fire cannot reach the tank 1 or heat cannot readily affect the same.

It will be noted that an inverted cup-shaped member 20 is mounted above the opening 15 to protect the opening against the entrance of foreign matter and incidentally to properly direct the water from opening 15. In case the thermometer 12 gives an alarm, water may be turned on and the result will be a comparatively thick wall of water surrounding tank 1 and an outside sheet of water covering the top and sides of the casing 6. In case there should be a fire near the tank or the temperature of the atmosphere should rise to an undesirable extent from the sun or other causes, water could be intermittently supplied to maintain the contents of the tank cool or below the danger point.

What I claim is:—

1. A tank of the character described comprising an inner container, an outer casing

spaced from the container, means for directing a cooling and fire extinguishing medium into the space between the container and the casing, said casing being open at the top 5 for permitting said medium to flow out the top, together with means to cause said medium to spread out evenly over the casing.

2. A tank of the character described comprising a container, a covering member therefor, means for directing water to the top of said covering member, and means for causing the water passing over the top of the covering member to flow in a substantially even sheet over the entire covering 10 member and container.

3. A tank of the character described comprising a container, a casing surrounding the container and spaced therefrom, said casing having a top spaced from the top of the container, said top having a centrally arranged opening, means for directing water 15

into the bottom of said casing so that it may rise in the space between the casing and the container and eventually flow out the opening at the top of the casing, and means arranged on the top of the casing for causing the water to flow over the casing in a substantially even sheet.

4. A tank of the character described comprising a container, a casing spaced from the container and covering the entire container on the top and sides, said casing being connected with the container at the bottom whereby a space will be provided between the container and the casing except at the bottom, said casing having an opening centrally of the top, a plurality of annular arc-shaped water deflecting rings mounted on said top, and means for directing water to the space between the casing and the container.

JOHN WESLEY KERLIN.
